US00D924190S

(12) **United States Design Patent** (10) **Patent No.:** **US D924,190 S**
Matsuoka et al. (45) **Date of Patent:** **** Jul. 6, 2021**

(54) **PHONE**

(71) Applicant: **Google LLC**, Mountain View, CA (US)

(72) Inventors: **Yoshimichi Matsuoka**, Sunnyvale, CA (US); **Alberto Villarreal Bello**, San Jose, CA (US); **Vincent Claudepierre**, San Francisco, CA (US); **Max Ken Yoshimoto**, Sunnyvale, CA (US); **Ji Hye Bae**, Mountain View, CA (US)

(73) Assignee: **GOOGLE LLC**, Mountain View, CA (US)

(**) Term: **15 Years**

(21) Appl. No.: **29/690,804**

(22) Filed: **May 10, 2019**

Related U.S. Application Data

(63) Continuation of application No. 29/604,921, filed on May 22, 2017, now Pat. No. Des. 853,370.
